UNITED STATES PATENT OFFICE

DESIGN FOR A TOY

Edward J. Stewart, Chicago, Ill.

Application July 6, 1937, Serial No. 70,278

Term of patent 14 years

To all whom it may concern:

Be it known that I, Edward J. Stewart, a citizen of the United States, residing at Chicago, in the county of Cook and State of Illinois, have invented a new, original, and ornamental Design for a Toy, of which the following is a specification, reference being had to the accompanying drawing forming a part thereof.

The figure is a perspective view of the toy showing my new design.

The dominant features of the design reside in the spirally wound wire formed into an elongated substantial bell shape extending from the end of an elongated cylindrical slotted handle member, the smaller end of the bell-shaped wire being substantially greater in diameter than the diameter of the handle member and being in axial alignment therewith and the handle member having a finger piece extending through the slot thereof and a plunger normally extending above the bell end of the handle member in axial alignment therewith.

I claim:

The ornamental design for a toy substantially as shown and described.

EDWARD J. STEWART.
